UNITED STATES PATENT OFFICE.

JAMES DYKES, OF NEW ROCKFORD, NORTH DAKOTA.

CABLE-STRETCHER.

1,118,539.

Specification of Letters Patent.

Patented Nov. 24, 1914.

Application filed July 21, 1913. Serial No. 780,289.

To all whom it may concern:

Be it known that I, JAMES DYKES, citizen of the United States, residing at New Rockford, in the county of Eddy and State of North Dakota, have invented certain new and useful Improvements in Cable-Stretchers, of which the following is a specification.

This invention relates to devices for stretching the pull cable over a train of sand cars or the like to enable the cable to be expeditiously coupled to the unloading plow or scraper, and has for one of its objects to simplify and improve the construction and increase the efficiency and utility of devices of this character.

Another object of the invention is to provide a simply constructed device which may be readily coupled to the track and whereby the pull cable is unreeled from the winding drum as the train is moved into position.

Another object of the invention is to provide a simply constructed device whereby the holding means for the pull cable may be quickly installed in position, and the pull cable released when the stretching operation is completed.

With these and other objects in view the invention consists in certain novel features of construction as hereinafter shown and described and then specifically pointed out in the claims and in the drawings illustrative of the preferred embodiment of the invention.

Figure 1 is a plan view of a portion of a railway track with the improvement applied. Fig. 2 is a side elevation of the parts shown in Fig. 1. Fig. 3 is an enlarged side elevation of the improved anchor grip connected to a rail, the rail being in transverse section. Fig. 4 is a plan view of the parts shown in Fig. 3 with the rail in section on the line 4—4 of Fig. 3. Fig. 5 is a perspective view of the attachment employed for maintaining the anchor cable in elevated position.

Corresponding and like parts are referred to in the following description and indicated in all the views of the drawings by the same reference characters.

In making "fills" in connection with railway construction and similar operations, earth or sand is usually employed as a filler and first deposited upon platform cars made into a train and coupled together, the rear car being provided with a plow or scraper and the forward car provided with a wind-

ing drum, and with a locomotive to draw the train thus made up. A pull cable is connected to the winding drum at one end and to the plow or scraper at the other end and then as the winding drum is operated and the cable wound up the plow or scraper is drawn over the cars toward the winding drum and thus consecutively discharges the loads from the cars.

When ready to discharge the cars, the cable, which is generally 1000 feet or more long, must first be unwound from the drum and disposed over the entire train and coupled to the plow or scraper and this has heretofore required the labor of a large number of men, besides taking a relatively long period of time, and holding the train idle during the stretching operation.

The principal object of the present invention is to cause the pull cable to be stretched over the loaded cars without requiring it to be handled, and without the necessity for stopping the train except for very short time.

The improved device comprises a crotch cable to which the main pull cable is connected, means for anchoring the terminals of the crotch cable to the track, and means for supporting the crotch cable at a suitable distance above the rails and spaced apart far enough to permit the cars to pass.

The crotch cable portion of the improved device is represented as a whole at 10 and is provided with rings 11 at its terminals and an eye 12 through which the crotch cable is sliable by its "bight" portion. The terminal eyes 11 of the crotch cable are arranged to be connected to suitable anchor grip devices attached to the rails represented conventionally at 13 and between a pair of the ties represented conventionally at 14. The anchor grips are precisely alike except that they are made rights and lefts and the description of one will suffice for both. Each anchor grip comprises a base member 15 adapted to be disposed beneath one of the rails 13 and bent into a hook 16 for engaging around the inner edge of the flange of the rail and to extend beyond the rail at the opposite end. Riveted or otherwise attached to the upper face of the inner end of the base member 15 is a spacing block 17, and pivoted at 17' upon the spacing block is a combined grip and cable receiving member 18. The pivot 17' extends through the three members 15—16—18 so that the mem-

ber 18 is free to swing laterally upon the pivot. At its inner end the member 18 is extended obliquely to the longitudinal plane of the member as represented at 19 so that 5 a wedge-shaped gripping point 20 is produced for engaging against the web of the rail.

The distance between the pivot 17' and the gripping point 20 is greater than the distance 10 between the pivots and the web of the rail, so that when the member 15 is disposed beneath the flange of the rail with the hook 16 engaging the flange the point 20 will engage against the web of the rail at the opposite side and thus firmly anchor the base member 15 and the upper member 18 to the rail when strain is applied in the direction of the arrow, as will be obvious, while at the same time the device can readily be released 15 when the strain is removed by simply reversing the movement of the member 18 upon its pivot 17'. The outer portion of the member 18 is preferably tapered as shown, and is provided with a link 21 to receive a hook 22 with which the terminal hooks 11 of the crotch cable are engaged, as shown.

At points intermediate the crotch cable struts or supporting devices are employed 30 for supporting the crotch cable in elevated position at each side of the track and spaced at a sufficient distance apart to permit the cars to pass, and as the supporting devices are precisely alike the description of one 35 will suffice for both.

Each supporting device comprises a bar formed of a horizontal portion 23 and a vertical portion 24 preferably formed of T metal with the web cut away at one end and the part of the bar which remains bent into 40 a rail flange engaging hook 25. Riveted or otherwise secured at 26 to the horizontal portion 23 of the bar is a bearing plate 27, preferably formed of T metal with the web 45 presented upwardly, and long enough to extend over a pair of the ties 14, and bear upon their upper faces as shown. Swiveled through the web portion of the plate 27 is a bar 28 threaded to receive an adjusting nut 29. The bar 28 is inclined upwardly toward the hook 25 and is designed to bear beneath the ball and against the web of the rail and thus coact with the hook 25 to firmly 50 anchor the bar 23 to the rail, the nut 29 providing means whereby the member 28 may be firmly clamped against the rail and thus anchor the member 23 thereto, and likewise adapt the device to rails of various sizes. The horizontal portion 23 and the vertical 55 portion 24 of the bar are supported by diagonal braces 30 as shown.

Near the upper end the vertical portion 24 of the bar is provided with a swiveled I bolt 31 to receive a vertical supporting member 32 preferably formed of a section of

piping. The member 32 is provided with an internal wooden core 33 to stiffen and strengthen the member, and likewise provided with a hook 34 near its upper end to receive the crotch cable 10 and support the 70 same. By this simple means the crotch cable is firmly coupled by its terminals to the track and likewise supported for a suitable distance above the track, and when strain is applied to the ring 12 the crotch cable 75 will be retained in position and not only spaced above the track but spaced apart a sufficient distance to permit the cars to pass.

Attached to the ring 12 by a short section of chain 35 is a bar 36 having an open hook 37 at one end and an eye 38 at the other end. A pull cord 39 is connected to the eye 38. The hook 37 is designed to receive a swivel coupling 40 attached to the pull cable, a portion of which is represented 85 at 41. By this simple arrangement it will be obvious that so long as the pull cord 39 remains in a slack condition the pull cable 41 will remain attached to the member 36, but when it is desired to release the pull 90 cable a pull upon the cord 39 will draw the bar 36 into its upward position and reverse the position of the hook 37 and thus release the member 36 and the cable 41 coupled thereto, and enable the member 36 to be 95 coupled to the plow, not shown.

The crotch cable will be located opposite the end of the "fill" from which the cars are received, and as the locomotive and the first car which contains the winding drum 100 and its operating mechanism with the pull cable fully wound upon the drum, passes beneath the arched crotch cable the member 36 to which the cable is attached is coupled to the member 35 of the crotch cable with 105 the pull member 39 lying slack. Then as the train is moved forwardly the cable 41 is unwound from the winding drum and laid consecutively over the loaded cars until the last car which contains the plow or scraper 110 arrives beneath the crotch cable. The train is then stopped and the pull cable 39 actuated to reverse the position of the member 36 and release the hook 37 from the member 35. The hook 37 is then coupled to the plow 115 or scraper and the winding drum actuated to draw the plow or scraper consecutively over the cars and thus discharge the load.

The arrangement of the cars which contain the load, the winding drum and the plow together with the pull cable are so well known that it is not thought necessary to show these parts, the invention lying in the crotch cable and the manner of arranging and supporting the same.

Having thus described the invention, what is claimed as new is:

1. An apparatus of the class described comprising a crotch cable, anchor devices at the terminals of the crotch cable and adapt- 130

ed to engage the rails of a railway track, struts spaced apart and having means for receiving the crotch cable, means for coupling said struts to the rails of a railway 5 track, and means for coupling a pull cable to said crotch cable.

2. An apparatus of the class described comprising a crotch cable, means adapted to connect said crotch cable to the rails of a 10 railway track, strut supports each including a horizontal portion and a vertical portion, means for coupling said horizontal portion to the rails of a railway track, a strut bearing upon each of said supports, means for 15 coupling said struts to said supports, and means carried by said struts for receiving the crotch cable.

3. An apparatus of the class described comprising a crotch cable, means adapted to 20 connect said crotch cable to the rails of a railway track, strut supports each including a horizontal portion and a vertical portion, said horizontal portion having a rail flange engaging hook, a bearing member extending 25 transversely of said horizontal portion and adapted to engage the adjacent ties of a railway track, a rail engaging member carried by said bearing member, a strut bearing upon each of said supports, means for 30 coupling said struts to said support, and means carried by said struts for receiving the crotch cable.

4. An apparatus of the class described comprising a crotch cable, means adapted to

connect said crotch cable to the rails of a 35 railway track, strut supports each including a horizontal portion and a vertical portion, means for coupling said horizontal portion to the rails of a railway track, a strut bearing upon each of said supports, diagonal 40 braces connected to the horizontal and vertical portions of the strut support and between which the strut extends, means for coupling said struts to the vertical portion of said supports, and means carried by said 45 struts for receiving the crotch cable.

5. The combination with a railway track including the rails and ties, of supports each including a vertical portion and a horizontal portion, said horizontal portions each having 50 a terminal hook for engaging respectively with the flanges of the rails, a bearing member extending transversely of each of said horizontal portions and adapted to engage the adjacent ties, a rail engaging 55 member carried by each of said horizontal members, a strut bearing upon each of said horizontal portions, means for coupling said struts to said vertical portions, and means carried by said struts for receiving a crotch 60 cable.

In testimony whereof I affix my signature in presence of two witnesses.

JAMES DYKES. [L.S.]
